CRUCIBLE AND METHOD OF MAKING
CRUCIBLES

Robert J. Anicetti, Beverly, Mass., assignor to the
United States of America as represented by the
United States Atomic Energy Commission

Application March 20, 1945, Serial No. 583,769

19 Claims. (Cl. 263—48)

1

This invention relates to improvements in crucibles and methods of making crucibles. More particularly, this invention relates to improvements in crucibles and methods of making crucibles in which the bottom members may be replaced.

The general practice of molding or fashioning crucibles with the side walls integral with the bottom members, forming discharge outlets and finishing and hardening the crucibles in a furnace or kiln presents many difficulties as the operation requires skill and takes considerable time. Also crucibles formed in this manner have disadvantages, an important one being that if the bottom of a crucible is damaged the entire crucible must be scrapped.

The method that comprises the present invention may be readily carried out and if a bottom member of a crucible made in accordance with the present invention is damaged the bottom member may be removed from the member forming the side wall and the side wall fitted with another bottom member.

Accordingly the principal object of the present invention is to provide improvements in crucibles and methods of making crucibles.

Another object of the present invention is to provide improvements in crucibles and methods of making crucibles in which the bottom members may be readily replaced.

Other objects of the invention will be obvious and others will be apparent from the following description and accompanying drawing.

In the drawing:

Figure 1 is a vertical sectional view taken through the center line of a form of crucible embodying the invention.

Figure 2 is a vertical sectional view taken through the center line of another form of crucible embodying the invention.

The method of making a crucible in accordance with this invention comprises forming a separate side wall member from a length of cylindrical tube or pipe made by molding graphite or other suitable material into a tube or pipe and finishing and hardening by firing in a furnace or kiln or by drilling or coring the cylindrical tube or pipe from a finished and hardened block of suitable material such as a graphite electrode. A portion of the inner wall of the tube adjacent one end is machined. A separate bottom member is formed from a relatively flat disc-like member of graphite or other suitable material that has been finished and hardened by firing in a furnace or kiln. Suitable discharge outlets are formed in the bottom member and the surface that forms

the upper side of the bottom member is machined so that it slopes toward the discharge outlets to enable molten metal to be completely drained from the crucible. The lower side of the bottom member is flat. The periphery of the bottom member is machined so that the bottom member may be pressed into the end of the member forming the side wall with its periphery engaging the machined portion of the inner wall of the side wall member with a machine fit. The area of contact of the bottom member with the side wall member is substantially equal to the peripheral area of the bottom member and with the machine fit is sufficient to retain the bottom member in the side wall member without the use of flange means or the like at the periphery of the bottom member.

With this method the side wall members and bottom members may be easily made as separately finished members and then fitted together to form the completed crucible. If during use the bottom member is damaged, the bottom member is replaceable by either removing the bottom member or by cutting off the side wall member above the bottom member, machining the inner wall of the side wall member adjacent one end, and pressing another bottom member into the machined end of the side wall member. The side wall member will outlast several crucibles made in the ordinary manner.

Referring to Figure 1 of the drawing, reference character 1 indicates a side wall member comprising a finished and hardened length of cylindrical tube of graphite or other suitable material having an inner wall 2. A portion of the inner wall adjacent one end is machined to a larger dimension 3 forming a shoulder 4. A finished and hardened disc-like bottom member 5 of graphite or other suitable material is provided with a discharge outlet fitted with a bushing 6. The upper surface of the bottom member is machined to slope toward the discharge outlet as shown at 7. The lower surface 8 of the bottom member is flat. The periphery of the bottom member is machined and the bottom member is pressed into the side wall against the shoulder with its machined periphery engaging the machined portion of the inner wall of the side wall member with a machine fit. The area of engagement of the periphery of the bottom member and the machined portion of the side wall and the closeness of the fit are sufficient to securely retain the bottom member in position in the side wall member.

Referring to Figure 2 of the drawing in which is shown another embodiment of the invention

reference character 10 indicates a side wall member comprising a finished and hardened length of cylindrical tube of graphite or other suitable material having an inner wall 11. A portion 12 of the inner wall adjacent one end is machined to form a slight taper, of the order of several thousandths per inch. The taper as shown in the drawing is exaggerated to illustrate this feature. A finished and hardened disc-like bottom member 13 of graphite or other suitable material is provided with a discharge outlet fitted with a bushing 14. The upper surface of the bottom member is machined to slope toward the discharge outlet as shown at 16. The lower surface 16 of the bottom member is flat. The periphery of the bottom member is machined to the same taper as the machined portion of the inner wall of the side wall member and the bottom member is pressed into the side wall member with its tapered periphery engaging the tapered portion of the side wall member with a machine fit. The inner wall of the side wall member is machined to a sufficient length to permit the entire machined periphery of the bottom member to engage it. The area of engagement of the periphery of the bottom member with the side wall member, the degree of taper, and the closeness of the fit are sufficient to securely retain the bottom member in the side wall member.

While preferred embodiments of the invention have been shown it is to be understood that changes and variations may be made without departing from the spirit and scope of the invention as defined in the appended claims.

What is claimed is:

1. The method of making a crucible comprising forming a separate side wall member by machining a portion of the inner wall adjacent one end of a length of hardened and finished tube, forming a separate bottom member by machining the periphery of a hardened and finished disc-like member, and pressing the bottom member into the side wall member with the machined periphery of the bottom member securely engaging the machined portion of the inner wall of the side wall member with a machine fit.

2. The method of making a crucible comprising forming a separate wall member by machining a portion of the inner wall adjacent one end of a length of hardened and finished tube, forming a separate bottom member by machining the periphery of a hardened and finished disc-like member and pressing the bottom member into the side wall member with the machined periphery of the bottom member securely engaging the machined portion of the inner wall of the side wall member with a machine fit over an area of contact sufficient to securely retain the bottom member in position.

3. The method of making a crucible comprising forming a separate side wall member by machining a portion of the inner wall adjacent one end of a length of hardened and finished tube to a larger inner dimension, forming a separate bottom member by machining the periphery of a hardened and finished disc-like member and pressing the bottom member into the side wall member with the machined periphery of the bottom member securely engaging the machined portion of the inner wall of the side wall member with a machine fit.

4. The method of making a crucible comprising forming a separate side wall member by machining a portion of the inner wall adjacent one end of a length of hardened and finished tube to a

larger inner dimension, forming a separate bottom member by machining the periphery of a hardened and finished disc-like member and pressing the bottom member into the side wall member with the machined periphery of the bottom member securely engaging the machined portion of the inner wall of the side wall member with a machine fit over an area of contact sufficient to securely retain the bottom member in position.

5. The method of making a crucible comprising forming a separate side wall member by machining a portion of the inner wall adjacent one end of a length of hardened and finished tube to a larger inner dimension and forming a shoulder therein, forming a separate bottom member by machining the periphery of a hardened and finished disc-like member, and pressing the bottom member into the side wall member against the shoulder with the machined periphery of the bottom member securely engaging the machined portion of the inner wall of the side wall member with a machine fit.

6. The method of making a crucible comprising forming a separate side wall member by machining a portion of the inner wall adjacent one end of a length of hardened and finished tube to a larger inner dimension and forming a shoulder therein, forming a separate bottom member by machining the periphery of a hardened and finished disc-like member, and pressing the bottom member into the side wall member against the shoulder with the machined periphery of the bottom member securely engaging the machined portion of the inner wall of the side wall member with a machine fit over an area of contact sufficient to securely retain the bottom member in position.

7. The method of forming a crucible comprising forming a separate side wall member by machining a portion of the inner wall adjacent one end of a length of hardened and finished tube to form a taper, forming a separate bottom member by machining the periphery of a hardened and finished disc-like member to substantially the same taper as the machined portion of the side wall member, and pressing the bottom member into the side wall member with the machined periphery of the bottom member securely engaging the machined portion of the inner wall of the side wall member with a machine fit.

8. The method of forming a crucible comprising forming a separate side wall member by machining a portion of the inner wall adjacent one end of a length of hardened and finished tube to form a taper, forming a separate bottom member by machining the periphery of a hardened and finished disc-like member to substantially the same taper as the machined portion of the side wall member, and pressing the bottom member into the side wall member with the machined periphery of the bottom member securely engaging the machined portion of the inner wall of the side wall member with a machine fit over an area of contact sufficient to securely retain the bottom member in position.

9. A crucible comprising a separate tubular side wall member having a portion of the inner wall adjacent one end machined, a separate bottom member comprising a disc-like member the periphery of which is machined, with the bottom member pressed into the side wall member with the machined periphery of the bottom member securely engaging the machined portion of the

inner wall of the side wall member with a machine fit.

10. A crucible comprising a separate tubular graphite side wall member having a portion of the inner wall adjacent one end machined, a separate graphite bottom member comprising a disc-like member the periphery of which is machined, with the bottom member pressed into the side wall member with the machined periphery of the bottom member securely engaging the machined portion of the inner wall of the side wall member with a machine fit.

11. A crucible comprising a separate tubular graphite side wall member having a portion of the inner wall adjacent one end machined, a separate graphite bottom member having a flat lower surface comprising a disc-like member the periphery of which is machined, with the bottom member pressed into the side wall member with the machined periphery of the bottom member securely engaging the machined portion of the inner wall of the side wall member with a machine fit.

12. A crucible comprising a separate tubular graphite side wall member having a portion of the inner wall adjacent one end machined, a separate graphite bottom member comprising a disc-like member the periphery of which is machined, with the bottom member pressed into the side wall member with the machined periphery of the bottom member securely engaging the machined portion of the inner wall of the side wall member with a machine fit, the area of contact of the bottom member with the side wall member being sufficient to securely retain the bottom member in position.

13. A crucible comprising a separate tubular side wall member having a portion of the inner wall adjacent one end machined to a larger inner dimension, a separate bottom member comprising a disc-like member the periphery of which is machined, with the bottom member pressed into the side wall member with the machined periphery of the bottom member securely engaging the machined portion of the inner wall of the side wall member with a machine fit.

14. A crucible comprising a separate tubular graphite side wall member having a portion of the inner wall adjacent one end machined to a larger inner dimension, a separate graphite bottom member, comprising a disc-like member the periphery of which is machined, with the bottom member pressed into the side wall member with the machined periphery of the bottom member securely engaging the machined portion of the inner wall of the side wall member with a machine fit.

15. A crucible comprising a separate tubular graphite side wall member having a portion of the inner wall adjacent one end machined to a larger inner dimension, a separate graphite bottom member, comprising a disc-like member the periphery of which is machined with the bottom member pressed into the side wall member with the machined periphery of the bottom member securely engaging the machined portion of the inner wall of the side wall member with a machine fit, the area of contact of the bottom mem-

ber with the side wall member being sufficient to securely retain the bottom member in position.

16. A crucible comprising a separate tubular graphite side wall member having a portion of the inner wall adjacent one end machined to a larger inner dimension and forming a shoulder member, a separate graphite bottom member comprising a disc-like member the periphery of which is machined, with the bottom member pressed into the side wall member in engagement with the shoulder member and with the machined periphery of the bottom member securely engaging the machined portion of the inner wall of the side wall member with a machine fit.

17. A crucible comprising a separate side wall member having a portion of the inner wall adjacent one end machined to form a taper, a separate bottom member comprising a disc-like member the periphery of which is machined to form approximately the same taper as the machined portion of the side wall member, with the bottom member pressed into the side wall member with the machined periphery of the bottom member securely engaging the machined portion of the inner wall of the side wall member with a machine fit.

18. A crucible comprising a separate graphite side wall member having a portion of the inner wall adjacent one end machined to form a taper, a separate graphite bottom member comprising a disc-like member the periphery of which is machined to form approximately the same taper as the machined portion of the side wall member, with the bottom member pressed into the side wall member with the machined periphery of the bottom member securely engaging the machined portion of the inner wall of the side wall member with a machine fit.

19. A crucible comprising a separate graphite side wall member having a portion of the inner wall adjacent one end machined to form a taper, a separate graphite bottom member comprising a disc-like member the periphery of which is machined to form approximately the same taper as the machined portion of the side wall member, with the bottom member pressed into the side wall member with the machined periphery of the bottom member securely engaging the machined portion of the inner wall of the side wall member with a machine fit, the area of contact of the bottom member with the side wall member being sufficient to securely retain the bottom member in position.
